PACKAGE HOLDER

Fredrick W. Schmiedeberg, Portland, Oreg.

Application August 30, 1946, Serial No. 694,046

2 Claims. (Cl. 248—311)

1

This invention relates to a package holder and has particular reference to a holder for a box of disposable tissue and the like.

The general object of the present invention is to provide a holder suitable for a box of disposable tissue which will hold the box in an accessible position on a wall surface in a house or in an automobile with one side of the box exposed in such manner that the tissue may easily be withdrawn therefrom. The present holder is especially designed to receive disposable tissue boxes of the type having a longitudinal slit in the middle of the box top for drawing tissue therefrom one sheet at a time, the sheets being interfolded within the box to project a portion of the next sheet each time one sheet is removed.

It is, therefore, a further object of the invention to provide a holder to support such a box of tissue on its side with the tissue dispensing slot freely exposed on the front side thereof and unobstructed by the support. Another object is to provide a tissue box holder which is of simple, inexpensive construction, neat in appearance, and which will grip a tissue box with sufficient firmness and rigidity to be suitable for automobile use and to permit tissue to be drawn therefrom in the manner described without dislodging the box from the holder when a pull is exerted on a piece of tissue. Another object is to provide a holder which will firmly grip a tissue box but from which the box may readily be released for replacement without difficulty. A still further object is to provide a holder of the type described having novel hanger elements adapted to hang either on hooks or screws or through holes or over the edge of a vertical flange or sheet.

With these and other objects in view, the present holder comprises a single resilient piece of plastic material or wire having supporting hooks formed in the ends thereof, and having various bends and convolutions formed therein for embracing a tissue box and the like firmly on the back, front, ends and bottom thereof without obstructing the tissue dispensing slot therein. The box is thereby gripped securely on five of its sides to hold it against dislodgment from jostling movements and from the pull exerted thereon each time a piece of tissue is removed therefrom, but with sufficient resilience to permit the easy removal and replacement of the box when empty.

The exact nature of the device and the details of its construction will be more readily understood with reference to the accompanying drawings, in which:

Figure 1 is a perspective view of a preferred

2

embodiment of holder formed according to the principles of the present invention and showing in phantom a disposable tissue box supported therein;

Figure 2 is a rear view of the device in perspective with the box shown in full lines and with portions of an automobile body included to show the manner of hanging the device therein; and

Figure 3 is a front elevation view showing the approximate shape assumed by the holder in relaxed condition after a box has been removed therefrom.

The numeral 10 designates a tissue box having a longitudinal slit 11 extending substantially the length of the box in the middle of one side for dispensing individual sheets of tissue 12. The holder for the box is formed from a single piece of flexible wire or plastic material having an eye 13 in each end thereof adapted to hang on a screw or hook received through the loop of the eye and also adapted to hang as a hook over the top edge of an upstanding sheet such as the sheet 14 in Figure 2. The sheet 14 in the present illustration is intended to represent a stiff vertical panel of paperboard or the like, usually found in modern automobiles extending from the floor up the front or side walls in front of the driver's seat and beneath the cowl. The numeral 15 may represent either the underside of the cowl, or 20 a glove compartment built into the cowl. If the sheet 14 does not have an exposed upper edge as shown, small slits or holes may be cut therein to receive therethrough the extreme ends of the strip material forming the eyes 13. These extremities 15 are each twisted rearwardly out of the general plane of the eye to form effective supporting hooks which may either be projected through openings in the sheet or hung across the upper edge of the sheet in the manner described.

From each of the eyes 13 the strip is formed to extend straight down behind the box in a vertical reach 16 to a right angular corner 17 from which it then extends horizontally along the 45 rear side of the box to the rear corner 19. Between the rear and front corners 19 and 21 a side portion 20 extends along the end of the box just below mid height, and from the corner 21 the strip curves downwardly at 22 just beneath the 50 slit 11 and across the front side of the box to a lower corner 23. From the corner 23 the strip extends rearwardly at 24 to an angle point 25 near the rear edge of the box. From the rear point 25 the strip then extends forwardly at 26 55 in the form of a V to a point 27 near the front

edge of the box so that the two portions 24 and the two portions 26, together with the two angular portions 25 and the angle point 27, form a W in a horizontal plane to provide bottom support for the box.

The holder is made to assume approximately the shape shown in Figure 3 whereby the resilient spring action throughout the length of the strip tends to bring the upright portions 16 and the eyes 13 on the two ends substantially together. In order to insert a box in the holder the sides 20 are sprung outwardly as shown in Figure 1 to cause the arms 16 to separate and assume approximately vertical positions with the eyes 13 spaced substantially as shown to provide relatively distantly spaced points of support for the holder and box. The spring action of the material thereby resiliently grips the ends of the box and exerts sufficient frictional force thereon to prevent the box from jostling out of the holder when the latter is installed in an automobile and to prevent the box from becoming dislodged or twisted in the holder when sheets of tissue are pulled through the slit 11.

It will be observed that the corners 24 and the front portions 22 are disposed immediately below and closely adjacent the ends of the slit 11 where the greatest resistance is usually encountered in withdrawing sheets of tissue through the slit. Thus, the front support furnished by portions 22 immediately adjacent these points of resistance acting in conjunction with the gripping effects exerted by the end portions 20, and the bracing effect of the back portions, tend to hold the box firmly and prevent it from tilting in the holder if a tissue is difficult to withdraw from the box. Since the various portions of the holder substantially encompass five sides of the box, unintentional movement within the holder is effectively prevented even though the holder be made of light and flexible material. The proximity of the upper part of portions 22 and the angles 21 to the ends of the slit 11 also holds in the front wall of the box beneath the slit to prevent the box from yielding to its normal tendency to tear at these points, the holder thereby serving as a reinforcement for the box at its weakest points.

The box is easily removed from the holder by pressing down on the end portions 20 with the thumbs and pressing up on the bottom of the box with the fingers, if there is sufficient free space above the holder. If a cowling or glove compartment 15 prevents the raising of the box in this manner, the holder and box together may readily be lifted away from the supporting sheet 14, in which case only sufficient upward movement is required to free the ends 15 from the sheet 14. In such case the holder is easily replaced with a new box therein by merely extending the thumbs over or alongside the eyes 13 to locate the top edge of the sheet 14 or the holes therein through which the ends 15 are to be extended.

It will be observed that the improved supporting action of the present holder is attained by the novel shaping and forming of a single strip of flexible material to provide stiffness and rigid-

ity where these qualities are needed so as to result in an efficient and inexpensive holder which is relatively easier to manufacture than conventional holders for such purposes. The strip ma-

5 terial of which the holder is formed may be of any available cross sectional shape, a circular cross section being preferred for wire and either a square or flat rectangular cross section being preferred in plastic material. There are no welds or attachments to work loose from vibration, and if plastic material is used there is no painting or 10 enameling required to protect against rust.

The device is capable of various changes and all such modifications within the scope of the ap- 15 pended claims are included in the invention.

Having now described my invention and in what manner the same may be used, what I claim as new and desire to protect by Letters Patent is:

1. A holder for a tissue box and the like having 20 a horizontal tissue withdrawal opening extending across a vertical side thereof, comprising a single strip of resilient material formed to snugly engage five sides of said box, said strip having a mid portion extending transversely and longitudinally in a horizontal plane to form a bottom support embracing a substantial area of the bottom of said box, portions of said strip extending upwardly and laterally from said bottom support to embrace and confine the front of said box 25 adjacent the ends of said opening, portions of said strip extending across the ends of said box at approximately mid height and thence laterally toward each other across the back side of said box, said last named portions being formed to 30 spring together by the resilience of said bottom support to grip the ends of said box, straight vertical ends on said last named portions extending upwardly across the back side of said box, and deformed eyes constituting hooks in the ends 35 of said strip for suspending said holder, said single strip of material constituting the sole supporting and confining member in said holder.

2. A package holder formed in its entirety from 40 a single strip of flexible material, said strip having unrestrained vertical end portions extending upwardly on the back side of said holder and terminating in hanger ends, said strip having unrestrained portions in immediate continuation of said end portions constituting ends for said 45 holder, and said strip having a mid portion extending transversely and longitudinally across the bottom of said holder in continuation of the portions forming the ends of the holder and exerting a spring action on said unrestrained portions to pull said unrestrained portions inwardly to grip the ends of a package in said holder.
